(57) **CLAIM**

The ornamental design for a mandoline slicer with suction devices, as shown and described.

DESCRIPTION

FIG. 1 is a perspective view of a mandoline slicer with suction devices, showing the new design;

FIG. 2 is a front view of the mandoline slicer with suction devices of FIG. 1;

FIG. 3 is a right side view of the mandoline slicer with suction devices of FIG. 1;

FIG. 4 is a left side view of the mandoline slicer with suction devices of FIG. 1;

FIG. 5 is a back view of the mandoline slicer with suction devices of FIG. 1;

FIG. 6 is the top view of the mandoline slicer with suction devices of FIG. 1; and

FIG. 7 is the bottom view of the mandoline slicer with suction devices of FIG. 1.

FIG. 8 is a perspective view of another embodiment of a mandoline slicer with suction devices, showing the new design;

FIG. 9 is a front view of the mandoline slicer with suction devices of FIG. 8;

FIG. 10 is a right side view of the mandoline slicer with suction devices of FIG. 8;

FIG. 11 is a left side view of the mandoline slicer with suction devices of FIG. 8;

FIG. 12 is a back view of the mandoline slicer with suction devices of FIG. 8;

FIG. 13 is the top view of the mandoline slicer with suction devices of FIG. 8; and,

FIG. 14 is the bottom view of the mandoline slicer with suction devices of FIG. 8.
